UNITED STATES PATENT OFFICE.

HARRY T. ANDERSON AND SOREN HANSSON, OF BUTLER, PENNSYLVANIA, ASSIGNORS
OF ONE-THIRD TO CLEON M. HANNAFORD, OF RICHMOND, VIRGINIA.

COMBINED DRAFT-GEAR CARRIER AND CENTER-SILL TIE.

Application filed November 8, 1924. Serial No. 748,753.

The object of this invention is to provide means serving as a combined draft gear carrier and center sill tie for use in connection with the coupler mechanism of railway 5 cars.

In constructions commonly used the carrier plate crosses from side to side of the center sill and is bolted directly to the bottom flanges of the center sill members. We 10 refer now to center sills composed of two channel beams extending the length of the car and arranged parallel and so spaced apart as to receive a draw-bar and draft rigging. In the arrangement of carrier 15 plate referred to, the nuts often work loose and the draft gear carrier sometimes becomes displaced as a consequence, thus removing the substantial element of the support of the draft gear and resulting in considerable damage.

In the present invention the carrier is hooked on to the bottom flanges of the center sill members and fixed thereto in such way that the bolts are largely relieved of 25 strain, and even if the nuts should become detached, the other elements of the device serve to resist the displacement of the carrier.

The invention consists of a plate having 30 its ends bent over in the form of hooks to engage the bottom flanges of the center sill, the plate at one end directly engaging the adjacent sill flange and at its other end having a gib interposed between its hook 35 and its adjacent sill flange, the plate being bolted at both ends to said adjacent flanges, as we will proceed now to explain and finally claim.

In the accompanying drawings illustrating the invention, in the several figures of which like parts are similarly designated, Figure 1 is a front elevation showing the invention applied to an ordinary center sill part only of which is shown. Fig. 2 is a top plan view with the sill members in section and one of the bolts in section. Fig. 3 is a front elevation illustrating the mode of application of the plate or carrier. Fig. 4 is a central cross section of 45 the plate or carrier.

The center sill members 1 may be of the usual channel beam type, having bottom flanges 2, these sill members being arranged in any usual or approved way.

3 is the plate which forms the draft gear

carrier and center sill tie, the same being of suitable metal and of proper shape to function as herein explained, and having the longitudinal reinforcement 4 if desired. One end of the plate is turned up above the 60 top level of the plate to form the hook 5 which is adapted to engage the flange of one of the sill members, and the other end of the plate is likewise turned up but at a higher elevation to form the hooked member 6, the distance between the inner sides of these hooks being greater than the distance between the outside edges of the flanges of the sill members, so that the carrier plate may be mounted upon the flanges 65 by applying the larger hook 6 over the adjacent flange and then moving the plate in the direction of the smaller hook 5 and then lifting the smaller hook into engagement with the flange of its adjacent sill member, 70 and then reversing the movement so as to pull the hook 5 into intimate engagement with its adjacent flange. In order to secure the plate in position, the gib 7 is interposed between the hook 6 and the flange of 75 its adjacent sill member so as to occupy the space between said hook and the top of the flange, and said gib has its outer edge enlarged, as at 8, by folding over the metal of the gib, or otherwise thickening it, so as to 80 fill in the space between the curve in the hook member 6 and the outer edge of the flange and engage both.

The flanges 2 are provided with bolt holes 90 preferably of circular formation, and the plate also is provided with circular holes 10, as shown at the left hand side Figs. 1 and 2 to receive the bolts 11, the heads of which are arranged on the tops of the flanges and the nuts below the carrier plate. The gib 95 and the plate at the right-hand side are made with non-circular bolt holes 12 to receive similar bolts 11. The provision in the flanges 2 of circular holes serves to hold the bolts in place, while the non-circular holes 100 in the plate and gib serve to remove any possibility of shear on the bolts by movement of the plate and gib.

In assembling the parts, the heads of the bolts 11 are arranged to present a flat surface against the edges of the hooks 5 and 105 6 so as to prevent the turning of the bolts.

By the construction described, the draft gear carrier plate is securely held in place, and in addition it serves to tie together the 110

center sill beams in such way and to such extent as to prevent them from spreading.

The details of construction are variable within the principle of the invention and 5 the claims following.

What we claim is:—

1. A combined draft gear carrier and center sill tie, comprising a plate having hooked ends adapted to reach over the bottom flanges of the center sill members, one 10 of the hooked ends constructed to closely fit one flange and the other hooked end of larger dimensions, a gib interposed between the larger hooked end and the flange, and 15 bolts passing through the flange and carrier plate on one side and through the gib, flange and carrier plate on the other side, the hooked ends being brought into engagement with the sill flanges by lengthwise movement of the plate and such engagement secured by the gib and bolts.

2. A combined draft gear carrier and center sill tie, comprising a plate having hooked ends adapted to reach over the bottom 20 flanges of the center sill members, one of the hooked ends constructed to closely fit one flange and the other hooked end of larger dimensions, a gib having an enlarged 25 outer edge and interposed between the larger hooked end and the flange and engaging both, and bolts passing through the flange and carrier plate on one side and through the gib, flange and carrier plate on the other 30 side, the heads of the bolts fitting square against the edges of the hooked end.

3. A combined draft gear carrier and center sill tie, comprising a plate having hooked 35 ends adapted to reach over the bottom

flanges of the center sill members, one of the hooked ends constructed to closely fit one 40 flange and the other hooked end of larger dimensions to permit the plate to be moved lengthwise to secure the engagement of its hooked ends with the sill flanges, a gib interposed between the larger hooked end and 45 the flange, and bolts passing through the flange and carrier plate on one side and through the gib, flange and carrier plate on the other side, one of the elements described 50 having non-circular bolt holes.

4. A two piece combined draft gear carrier and center sill tie, comprising a plate having its opposite ends provided with hooks of different dimensions and adapted to hook over the bottom flanges of a center sill by 55 lengthwise movement of the plate, and a gib interposed between one of said hooks and the adjacent sill flange.

5. A two piece combined draft gear carrier and center sill tie, comprising a plate 60 having its opposite ends provided with hooks, one of said hooks of proper dimensions to embrace a sill flange and the other hook of larger dimensions, and a gib adapted to be interposed between said larger hook 65 and the sill flange adjacent thereto to effect engagement of said larger hook and said adjacent flange and draw the smaller hook into intimate engagement with its adjacent sill flange by lengthwise movement of the 70 plate.

In testimony whereof we have hereunto set our hands this 4 day of November A. D. 1924.

HARRY T. ANDERSON.
SOREN HANSSON.
